DESIGN FOR A PADLOCK

Kenly C. Bugg, Farmington, Mo.

Application November 9, 1938, Serial No. 80,977

Term of patent 14 years

To all whom it may concern:

Be it known that I, Kenly C. Bugg, a citizen of the United States, residing at Farmington, in the county of Saint Francois and State of Missouri, have invented a new, original, and ornamental Design for a Padlock, of which the following is a specification, reference being had to the accompanying drawing, forming a part thereof.

I claim:

The ornamental design for a padlock, as shown.

KENLY C. BUGG.
